[57] CLAIM

The ornamental design for a contour post for signs, as shown and described.

DESCRIPTION

FIG. 1 is a perspective view showing a first embodiment of our contour post for signs, shown broken intermediate the ends to denote indeterminate length;

FIG. 2 is a front view thereof;

FIG. 3 is a side view thereof, the other side being a mirror image;

FIG. 4 is a back view thereof;

FIG. 5 is an end view thereof, the other end being a mirror image;

FIG. 6 is an end view thereof with the end uncovered to show interior detail;

FIG. 7 is a perspective view showing a second embodiment of our contour post for signs, shown broken intermediate the ends to denote indeterminate length; and

FIG. 8 is a front view thereof;

FIG. 9 is a side view thereof, the other side being a mirror image;

FIG. 10 is a back view thereof;

FIG. 11 is an end view thereof, the other end being a mirror image; and,

FIG. 12 is an end view thereof with the end uncovered to show interior detail.
